UNITED STATES PATENT OFFICE.

FRANK THEISS, OF IRVINGTON, NEW JERSEY, ASSIGNOR TO FRANK THEISS CO., OF NEWARK, NEW JERSEY, A FIRM.

DESIGN FOR A MUSICAL-INSTRUMENT CASE.

42,984.

Specification for Design.

Patented Sept. 3, 1912.

Application filed June 21, 1912. Serial No. 705,132. Term of patent 14 years.

To all whom it may concern:

Be it known that I, FRANK THEISS, a citizen of the United States, residing at Irvington, in the county of Essex and State of New Jersey, have invented a new, original, and ornamental Design for Musical-Instrument Cases, of which the following is a specification, reference being had to the accompanying drawing, forming part thereof.

The figure is a top view of a musical instrument case, showing my new design.

I claim—

The ornamental design for a musical instrument case, as shown.

FRANK THEISS.

Witnesses:

HOWARD P. KING,
FRANCES E. BLODGETT.
